[57] ABSTRACT

An article or wearing apparel such as a belt buckle provided with an ornament on the front member and an indicator that is movable around the front member to any one of a plurality of predetermined positions, each of which positions being intended to convey a different message.

4 Claims, 8 Drawing Figures

BELT BUCKLE

DESCRIPTION OF THE INVENTION

This invention relates to articles of wearing apparel such as belt buckles, or the like provided with a feature such as a movable indicator which may be placed in a position to denote a message by the wearer.

An object of this invention is to provide an improved article of wearing apparel such as a belt buckle, or the like with an adjustable indicator, the different positions of the indicator being intended to convey different messages.

Another object of this invention is to provide an improved article of wearing apparel such as a belt buckle, or the like which is provided with an adjustable indicator, said article being made of metal, plastic, wood, or the like shaped so that it may be economically and efficiently manufactured.

Still another object of this invention is to provide an article of wearing apparel such as a belt buckle, or the like with an adjustable medallion on the front thereof which may be decorated with a monogram, sign of the zodiac or any other sign adaptable to be exhibited thereon and which is adjustable to any one of a plurality of positions intended to convey different messages.

Other and further objects of this invention will be apparent to those skilled in the art to which it relates from the following specification, claims and drawing in which, briefly:

FIG. 1 is a front view of this device assembled with a belt which is shown partially broken away;

FIG. 2 is a back view of this device as assembled with the belt;

FIG. 3 is a side view of this device and the belt attached thereto;

FIG. 4 is a vertical sectional view of an embodiment of this invention taken along the line 4—4 of FIG. 1;

FIG. 5 is a vertical sectional view of this device similar to that shown in FIG. 4, showing the front of the device in released position so that the indicator supporting member may be turned in any of its predetermined positions;

FIG. 6 is an exploded view of this device;

FIG. 7 is a view taken along the line 7—7 of FIG. 6; and

FIG. 8 is a view taken along the line 8—8 of FIG. 6.

Referring to the drawing in detail reference numeral 10 designates the adjustable circular body member of this device to which the indicator 11 which may be in the shape of a cross, for example, is attached. The indicator may have any one of a number of different shapes intended to serve as an indicator or as an ornament. The member 10 may be made of metal, plastic or similar materials and it may be made on a punch press, die cast or molded as desired.

A large recess is provided in the center of the member 10 and the front member 12 which may be a medallion, monogram with jewels attached, or the like, is positioned in this recess to protrude slightly therefrom. The front member 12 may also be made of metal, plastic, or the like, and it may be made by punch press, molded or die cast as desired. A stud 13 which has a predetermined geometric shape such as that of a hexagon, octagon, or the like, is attached to the back surface of the front member 12 by soldering, welding, gluing, or similar process. The stud 13 extends through a

hole 14 formed in the upstanding part 10a of the member 10 and a washer 15 is fixed in a groove in this stud just below the hole 14 so that this washer engages the part 10a of member 10 during the operation of this device as will be described hereinafter.

The adjustable member 10 is provided with a skirt 10b which extends around the flange 16a of the base 16 when the parts of this device are assembled as shown in FIG. 4. The base or bottom member 16 is provided with a belt-receiving loop 16b and a hook 16c. One end 10 of the belt 17 is looped around the loop 16b as shown in FIG. 3 and the other end of the belt which is provided with holes 17a is adapted to be engaged by the hook 16c in any one of these holes as shown in FIG. 2. 15 Thus, when the belt is worn around the waist of the wearer the ends thereof are assembled as shown in FIGS. 2 and 3 to hold the belt and this device assembled.

The base member 16 is provided with a cavity 18 that 20 is surrounded by wall structure 19 having a predetermined geometric shape on the outside thereof which corresponds to the internal geometric shape of the recess 10c provided in the member 10. Thus, when the wall structure 19 extends into the recess 10c, member 10 is fixed with respect to the base member 16 and under these conditions the member 10 is not adjustable with respect to the base member 16. Wall structure 19 is provided with a top 19a and a hole which is of the same geometric shape as the external shape of the stud 13, is provided in this top. Thus, the front member 12 to which the stud 13 is attached, is not rotatable with respect to the base member 16. However, the stud 13 is 25 slidable in the hole provided in the top 19a. By pressing on the washer 20 which is attached to the bottom of the stud 13 by the screw 21, the stud 13 and front member 12 is moved upward against the tension of the spring 22 and the washer 15 is brought into engagement with the member 10a so that the adjustable member 10 is moved upward and the recess 10b thereof is 30 dislodged from the top of the wall structure 19. Thereafter the member 10 which carries the indicator 11 may be adjusted to any one of a predetermined number of angles as determined by the shape of the wall structure 19 and recess 10b.

40 While I have shown and described a preferred embodiment of the invention it will be understood that the invention is capable of modification and variation from the form shown so that its scope should be limited only by the proper scope of the claims appended hereto.

50 What I claim is:

1. A belt buckle having an adjustable member with an indicator attached thereto, the combination comprising a base member having means on its backside for gripping a belt, said base member having a cavity in the center thereof extending away from said belt, said cavity being surrounded by wall structure of predetermined external geometric shape, an adjustable member positioned on the outside of said base member, said adjustable member having a recess facing said base member, said recess being of said predetermined geometric shape for receiving said wall structure, a front member having a stud attached thereto, a portion of said stud extending into said cavity, means attached to said stud for engaging said adjustable member so that the recess of said adjustable member is dislodged from said wall structure when pressure is applied to said stud and said adjustable member is free to rotate to position the indicator.

cator thereof in any one of a plurality of predetermined positions.

2. A belt buckle as set forth in claim 1, further characterized in that said stud holds said front member to prevent rotation of said front member with respect to said base member.

3. A belt buckle as set forth in claim 2, further characterized in that said stud is of predetermined geomet-

ric shape, slidable in a hole of the same shape in said base member to prevent said stud and said front member from rotating with respect to said base member.

5 4. A belt buckle as set forth in claim 3, further comprising a spring attached to said stud normally holding said recess of said adjustable member assembled with said recess.
